COMBINED POWER CAN OPENER AND AGITATOR

Salvatore J. Manno, Brooklyn, N. Y.

Application September 23, 1952, Serial No. 311,070

3 Claims. (Cl. 259—108)

1

This invention relates to new and useful improvements and structural refinements in power driven devices for opening cans, agitating, etc., such as may be used in homes, restaurants, and the like.

In particular, the invention contemplates the combination, in a single tool, of a power driven can opener, an agitator for beverages such as milk shakes, etc., a knife sharpener, and a manual bottle opener, all these devices being conveniently arranged and available for instantaneous, expeditious use.

With the above more important objects and features in view and such other objects and features as may become apparent as this specification proceeds, the invention consists essentially of the arrangement and construction of parts as illustrated in the accompanying drawings, in which:

Figure 1 is a side elevational view of the invention with the casing and cover thereof in an open position;

Figure 2 is a side elevational view, taken from the opposite side and illustrating the casing in its operative position, portions of the device being shown in section;

Figure 3 is a horizontal sectional view, taken substantially in the plane of the line 3—3 in Figure 2;

Figure 4 is a fragmentary elevational view of the container or can sustaining means;

Figure 5 is a fragmentary detail of an enlarged scale, illustrating the motor and clutch;

Figure 6 is a sectional view, taken substantially in the plane of the line 6—6 in Figure 2;

Figure 7 is a sectional detail, taken substantially in the plane of the line 7—7 in Figure 4, and

Figure 8 is a sectional detail, taken substantially in the plane of line 8—8 in Figure 4.

Like characters of reference are employed to designate like parts in the specification and throughout the several views.

Referring now to the accompanying drawings in detail, the invention is designated generally by the reference character 10 and embodies in its construction a vertically elongated housing 12 having a back portion 14 adapted to be secured to a wall, and also having a front wall 16.

The housing 12 is provided at the front, upper portion thereof with a casing 18 which is hinged to the housing at 20 so that it may be swung from an operative position adjacent the front wall 16 (see Figures 2, 3 and 6) to an inoperative position remote from the front wall (see Figure 1). A resilient clip 21 is provided for sustaining the casing in its operative position.

An agitator shaft 22 is rotatably journaled in a bracket 24 in the casing 18 and extends downwardly therefrom into a container 26 such as is

2

commonly used for milk shakes, or the like, it being understood, of course, that this container does not constitute a component of the invention.

5 The container 26 is supported at the bottom thereof by a bracket 28 which is pivotally mounted on a pin 30 carried by a slide 32. This slide is movable vertically in a slot 34 provided in the lower portion of the front wall 16 and is guided in 10 its movement by a channel-shaped guide 36 secured to the rear surface of the front wall. The bracket 28 is formed integrally with a cam 38 (see Figure 7) which is engageable with the guide 36 when the bracket is in its forwardly projected position, whereby to lock the bracket at the appropriate height to suit the container 26. However, by simply swinging the bracket 28 upwardly as shown at 40, the cam 38 is released from the guide 36 and the slide 32 may be shifted upwardly or downwardly as desired.

15 It is to be also noted that the agitator shaft 22 is preferably of a telescopic construction as indicated at 42 so as to accommodate containers 26 of different heights.

20 The upper edge of the container 26 is engageable by detent means 44 provided on the underside of the casing 18.

25 An electric motor 46 is mounted by suitable bracket means 48 in the housing 12 and has a drive shaft 50 which projects through a horizontal partition 52 in the upper portion of the housing and carries a drive pulley 54. This drive pulley has a convex periphery which is frictionally in engagement with a concave periphery of a driven pulley 56, the latter being rotatable on a stub shaft 58 secured to the partition 52.

30 The front wall 16 of the housing 12 and the adjacent side wall of the casing 18 are provided with registering slots (one of which is shown at 40 60 in Figure 1), whereby a portion of the driven pulley 56 may project into the casing 18 when the casing is in its operative position adjacent the front wall.

35 In that position the driven pulley 56 frictionally engages a floating pulley 62 which has a convex periphery to engage the concave periphery of the pulley 56. The pulley 62 is rotatably mounted on a pin 64 secured to an arm 66 which is swingably mounted on the aforementioned agitator shaft 22 and is urged by means of a tension spring 68 to a position wherein the pulleys 56, 62 are in operative engagement. The agitator shaft 22 carries a further pulley 70 which has a concave periphery to frictionally engage the drive pulley 54 and it will 40 be apparent from the foregoing that when the casing 18 is swung to its operative position adjacent the front wall 16, the engagement of the pulleys 56, 62 will impart a rotary drive motion from the motor 46 to the agitator shaft 22. However, when 45 the casing 18 is swung to its inoperative position,

the pulleys 56, 62 will be disengaged and the drive to the shaft 22 will be interrupted.

The power can opening means comprise a rotary drive member or gear 72 which is rotatably mounted on a stud shaft 74 rigidly secured to the underside of the partition 52. The gear 72 projects outwardly through a slot in the front wall 16 to operatively engage the upper edge or bead of a can 76 which is to be opened (see Figure 1) and the actual can lid severing operation is accomplished by a pair of stationary cutters 78 which are secured to a vertically swingable frame 80 pivoted to the partition 52 at 82. The frame 80 includes a cross member 84 and a compression spring 86 is positioned on the aforementioned stub shaft 74 between this cross member and the gear 72, so as to urge the frame 80 and the cutters 78 upwardly. However, the frame 80 is also provided with a downwardly extending yoke 88 equipped with an actuating button 90 which is disposed forwardly of the front wall 16 and is engageable by the can 76 when the latter is installed in position. In such event, the engagement of the can 76 with the button 90 draws the entire frame 80 downwardly so as to engage the cutters 78 with the lid of the can and, at the same time, drive means are established for the gear 72 through the medium of a clutch presently described for the purpose of rotating the gear 72 and the can therewith.

The aforementioned clutch means includes a pinion 90 which is freely rotatable and slidable on the drive shaft 50 of the motor 46 and is in engagement with the gear 72. The pinion 90 has a dog clutch member 92 engageable by a coacting clutch member 94, the latter being slideable on but rotatable with the shaft 50. This is achieved by means of a pin 96 which extends transversely through the clutch member 94 and is slidable in a slot 98 provided in the shaft 50. The clutch member 94 is formed with an annular groove which is engaged by a fork 100 secured to the frame 80, and as a result, when the frame 80 is swung downwardly, the clutch members 94, 92 are engaged and rotation is imparted to the gear 72 by the motor 46.

If desired, a guide and supporting bracket 102 may be secured to the front wall 16 to engage the underside of the top bead on the can 76 to effectively support the latter while it is being rotated by the gear 72.

When neither the agitating apparatus nor the can opening apparatus are being used, a hollow cover 104, hinged to the housing 12 at 20, may be swung to a closed position indicated at 106 in Figure 1.

The invention also contemplates the provision of means for sharpening knives, or the like, these means consisting of an abrasive wheel 108, preferably having a V-shaped periphery, this wheel being partially exposed in a recess 110 provided on the top 112 of the housing 12. The wheel 108 is rotatably mounted upon a shaft 114 secured to the top 112 in a swingable manner by a pivot pin 116, the shaft 114 normally being urged upwardly by a spring 118. However, when a knife, or the like, is applied to the exposed portion of the wheel 108 so as to press the same downwardly, the wheel 108 is frictionally engaged with the aforementioned drive pulley 54 and is rotated thereby.

The operation of the motor 46 is controlled by a suitable switch 120 mounted on one side of the housing 12, while the opposite side of the housing is provided with a manual bottle opener 122 of a conventional type.

It is believed that the advantages and use of the invention will be clearly understood from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

15. A kitchen utensil comprising a housing having a front wall, a casing connected to said housing and swingable toward and away from said front wall, a container supporting means provided on the front wall and on said casing, a rotatable agitating member carried by and extending downwardly from said casing, a can lid severing means provided on said front wall and including a rotary drive member, a motor in said housing, and means for selectively operatively connecting said agitating member and said drive member to said motor.
20. A kitchen utensil comprising a housing having a front wall, a casing connected to said housing and swingable from an operative position adjacent the front wall to an inoperative position remote therefrom, a container supporting means provided on the front wall, a rotatable agitating member carried by and extending downwardly from said casing, a can lid severing means provided on said front wall and including a rotatable drive member, a motor mounted in said housing and including a drive shaft, means for operatively connecting said drive shaft to said agitating member when said casing is in its operative position, means operatively connecting said rotary drive member to said drive shaft, said last mentioned means including a clutch, and means responsive to positioning of a cam in engagement with said lid severing means for automatically engaging said clutch.
25. A kitchen utensil comprising a housing having a front wall, a casing connected to said housing and swingable from an operative position adjacent said front wall to an inoperative position remote therefrom, a container supporting means provided on said front wall and on said housing, a rotatable agitating member carried by and extending downwardly from said casing, a spring-pressed floating pulley mounted in said casing and operatively connected to said agitating member for rotating the same, a motor in said housing, and a driven pulley rotatably mounted in said housing and operatively connected to said motor, said floating pulley being engageable with said driven pulley when said casing is in its operative position.
30. A kitchen utensil comprising a housing having a front wall, a casing connected to said housing and swingable from an operative position adjacent the front wall to an inoperative position remote therefrom, a container supporting means provided on the front wall, a rotatable agitating member carried by and extending downwardly from said casing, a can lid severing means provided on said front wall and including a rotatable drive member, a motor mounted in said housing and including a drive shaft, means for operatively connecting said drive shaft to said agitating member when said casing is in its operative position, means operatively connecting said rotary drive member to said drive shaft, said last mentioned means including a clutch, and means responsive to positioning of a cam in engagement with said lid severing means for automatically engaging said clutch.
35. A kitchen utensil comprising a housing having a front wall, a casing connected to said housing and swingable from an operative position adjacent said front wall to an inoperative position remote therefrom, a container supporting means provided on said front wall and on said housing, a rotatable agitating member carried by and extending downwardly from said casing, a spring-pressed floating pulley mounted in said casing and operatively connected to said agitating member for rotating the same, a motor in said housing, and a driven pulley rotatably mounted in said housing and operatively connected to said motor, said floating pulley being engageable with said driven pulley when said casing is in its operative position.
40. A kitchen utensil comprising a housing having a front wall, a casing connected to said housing and swingable from an operative position adjacent the front wall to an inoperative position remote therefrom, a container supporting means provided on the front wall, a rotatable agitating member carried by and extending downwardly from said casing, a can lid severing means provided on said front wall and including a rotatable drive member, a motor mounted in said housing and including a drive shaft, means for operatively connecting said drive shaft to said agitating member when said casing is in its operative position, means operatively connecting said rotary drive member to said drive shaft, said last mentioned means including a clutch, and means responsive to positioning of a cam in engagement with said lid severing means for automatically engaging said clutch.
45. A kitchen utensil comprising a housing having a front wall, a casing connected to said housing and swingable from an operative position adjacent said front wall to an inoperative position remote therefrom, a container supporting means provided on said front wall and on said housing, a rotatable agitating member carried by and extending downwardly from said casing, a spring-pressed floating pulley mounted in said casing and operatively connected to said agitating member for rotating the same, a motor in said housing, and a driven pulley rotatably mounted in said housing and operatively connected to said motor, said floating pulley being engageable with said driven pulley when said casing is in its operative position.
50. A kitchen utensil comprising a housing having a front wall, a casing connected to said housing and swingable from an operative position adjacent the front wall to an inoperative position remote therefrom, a container supporting means provided on the front wall, a rotatable agitating member carried by and extending downwardly from said casing, a can lid severing means provided on said front wall and including a rotatable drive member, a motor mounted in said housing and including a drive shaft, means for operatively connecting said drive shaft to said agitating member when said casing is in its operative position, means operatively connecting said rotary drive member to said drive shaft, said last mentioned means including a clutch, and means responsive to positioning of a cam in engagement with said lid severing means for automatically engaging said clutch.
55. A kitchen utensil comprising a housing having a front wall, a casing connected to said housing and swingable from an operative position adjacent said front wall to an inoperative position remote therefrom, a container supporting means provided on said front wall and on said housing, a rotatable agitating member carried by and extending downwardly from said casing, a spring-pressed floating pulley mounted in said casing and operatively connected to said agitating member for rotating the same, a motor in said housing, and a driven pulley rotatably mounted in said housing and operatively connected to said motor, said floating pulley being engageable with said driven pulley when said casing is in its operative position.
60. A kitchen utensil comprising a housing having a front wall, a casing connected to said housing and swingable from an operative position adjacent the front wall to an inoperative position remote therefrom, a container supporting means provided on the front wall, a rotatable agitating member carried by and extending downwardly from said casing, a can lid severing means provided on said front wall and including a rotatable drive member, a motor mounted in said housing and including a drive shaft, means for operatively connecting said drive shaft to said agitating member when said casing is in its operative position, means operatively connecting said rotary drive member to said drive shaft, said last mentioned means including a clutch, and means responsive to positioning of a cam in engagement with said lid severing means for automatically engaging said clutch.

SALVATORE J. MANNO.
